7 Claims. (Cl. 194—72)

This invention relates to prepayment mechanism for gas and electricity meters and for like purposes, and especially to mechanism adapted for operation by coins of more than one value without any adjustment of the mechanism being necessary to render it operable by such coins.

The invention has among its objects to provide improved coin holders of the kind provided with a plurality of coin slots adapted for the reception of coins of different values, wherein the coins are retained within the respective slots by spring pressure exerted in a direction parallel with the corresponding slots.

The invention is especially applicable to mechanism such as described in the specification of the co-pending application No. 668,950, filed May 2, 1933 from which this application is divided.

According to the invention in its application to coin-actuated mechanism adapted for alternative actuation by two coins, such as a shilling and a penny, the coin holder mechanism is provided with separate and adjacent coin slots and with separate strikers for actuation by the respective coins, the striker corresponding to the coin of smaller value is independently operable while the striker corresponding to the coin of higher value when actuated causes the actuation of the other striker.

The coin pockets may be so provided that while the pocket for the coin of lower value is such that the coin cannot be displaced from its position in the pocket on the clockwise movement of the coin holder, the coin pocket for the coin of higher value is open to the adjacent pocket of the coin of lower value, so that thus in the clockwise rotation of the coin holder after the insertion for example of a shilling, the coin does not remain parallel with the coin pocket, but on being thrust outwards by means of the helical spring to which the striker is subject, engages with the inner periphery of the coin holder casing and as the coin holder is rotated clockwise the coin is thus tilted to an angle whereby the outer edge of the coin comes to rest against the side of the adjacent penny pocket. In this operation the quantity wheels are both rotated to the same extent as would be the quantity wheel when engaged by the single striker on actuation by a coin of lower value. Thus the strikers are disengaged from the respective quantity wheels at exactly the same position as is the single striker when actuated by a coin of lower value. In this way the shilling is released at the same position as a penny to pass through the same discharge slot provided

in determined position in the lower part of the casing to drop into the coin receptacle beneath.

The invention further comprises the constructional features hereinafter described.

The invention is illustrated, by way of example, in the accompanying drawing.

Figure 1 is a sectional side elevation of a coin holder mechanism provided according to the invention.

Figure 2 is a rear elevation of the coin holder, partly in section.

Figure 3 is a sectional plan view of the coin holder mechanism.

Figure 4 represents perspective views of the two strikers provided in the coin holder.

In carrying the invention into effect according to the construction represented in the accompanying drawing in its application to a mechanism such as that described in the specification of the copending application No. 668,950, the price-changing disc *a* is provided in determined position with two parallel and juxtaposed slots *a*¹, *a*² of sizes corresponding respectively to a shilling and a penny, similar slots *b*¹, *b*², or an aperture being provided in the disc *b* forming part of the coin holder that is disposed on the inner face of the price-changing disc, it being understood that the coin holder is concentrically mounted upon the price-changing disc and is adapted in known manner to be rotated by means of a handle *c* mounted externally to the price-changing disc. The coin holder may in known manner comprise two parallel disposed plates *d*, *e* that extend outwardly from the disc *b* and are set in position transversely across the face of the disc at positions near a diametric line, the plates being conveniently diverted at right angles at one end for the formation of lugs by which the plates may be secured to the outer face of the disc *b*, while at the opposite or outer end one of the plates *d* may be bent to form an end wall *d*¹ for engagement with the other, and thus form a rectangular cavity within which the strikers *f*, *g* may be mounted to slide lengthwise and in planes parallel and adjacent to that in which the axis of the coin holder lies. The strikers may advantageously be provided to lie in the same plane, being for the main part of their length of a width or breadth approximately equivalent to one-half the width or breadth of the cavity within the coin holder, and being respectively adapted to move transversely to the axis of the coin holder by means of pins *g*¹, *f*¹ passing respectively through slots *e*¹, *e*² in vertical line provided in the one wall *e* of the

coin holder, the slots being provided in line transversely to the axis of the coin holder. The striker g is further constrained to move transversely to the axis of the coin holder by a second pin g^2 which also passes transversely through a slot in the wall e of the coin holder. The striker f is constrained to a similar movement by reason of its shape relatively to that of the striker g and the relative disposition of the two strikers in the coin holder. The pins g^1 , f^1 serve for the engagement of the lower ends of corresponding helical springs g^3 , f^2 , the upper end of each of which may be engaged upon a pin secured to or integral with the wall of the coin holder near the opposite end, so that thus the respective strikers may normally be maintained in their outermost position respectively out of engagement with the quantity wheels h , i . The striker f that is adapted to be actuated by a shilling is of slightly greater length than the striker g that is adapted to be actuated by a penny, so that thus the shilling striker at its upper end extends over the penny striker and forms an outwardly extending arm or pawl. Thus the arm or pawl of the shilling striker f extends outwardly from the end wall of the coin holder to engage the larger and outermost quantity wheel i , while the penny striker g which is disposed adjacent the end wall, is at its upper end provided with a shorter striker arm or pawl that is adapted to engage the adjacent smaller quantity wheel h . The shilling striker f is provided with a transversely disposed part f^3 in a determined position which is conveniently provided with a groove for the reception of the lower edge of the shilling coin on its introduction through the slot in the price-changing disc, and this transversely disposed part is normally disposed above a corresponding transversely disposed part g^4 immediately beneath and carried by the penny striker g . These respective transversely disposed parts it will be understood form the bottom of the adjacent coin pockets respectively for the coins of higher and lower value. The part g^4 is provided of greater thickness than the part f^3 and corresponding approximately to the width of the coin holder pocket, so that a penny may rest thereon at the side of the part f^3 . Inasmuch as the transversely disposed part g^4 forming the bottom of the pocket for the coin of lower value is disposed immediately beneath and in contact with the transversely disposed part f^3 forming the bottom of the pocket for the coin of higher value, it will be understood that when the coin of a higher value is introduced into the coin holder both strikers are caused to move downwards or inwards to engage the respective quantity wheels. Furthermore it will be understood that the penny striker at its upper end lies immediately beneath the overhanging part of the shilling striker, and thus any movement imparted to the shilling striker is necessarily imparted to the penny striker.

In operation, it will be understood that by inserting a penny, for example, through the appropriate slot and into the appropriate coin pocket, the penny striker g is depressed, so that its outwardly extending arm engages the appropriate quantity wheel h , and the penny remains parallel within the pocket until the coin is ejected through the discharge slot j^1 in the lower part of the casing j at which time the striker is also disengaged from the quantity wheel. Furthermore the transversely disposed part f^3 of the striker f is provided with a lat-

erally disposed upstanding portion f^4 defining the coin space and having the inner face inclined or bevelled outwardly. By inserting a shilling, for example, through the appropriate slot and into the appropriate coin pocket, both the shilling and penny strikers are depressed, whereby both the adjacent quantity wheels are engaged and as the coin holder is thereupon rotated the coin does not remain parallel with the pocket but being held against the inner periphery of the casing by reason of the effect of the helical springs by which the respective strikers are subject, the coin is tilted into a position in which it lies against the inclined surface of the portion f^4 with its outer edge in contact with the side of the adjacent penny pocket. The quantity wheels are thus rotated to an extent corresponding to that by which one of the wheels would be moved on actuation of the mechanism with a penny and the strikers disengage from the quantity wheels at exactly the same position on reaching the discharge slot j^1 in the lower part of the casing j as in the case of actuation by a penny.

At its forward end the transversely disposed part f^3 of the shilling striker is advantageously recessed to receive a roller f^5 which facilitates the entry of a coin into the corresponding coin pocket or recess.

It will be understood that the invention is not limited to the details of construction hereinbefore described, since these may be varied without departing from the scope of the invention as hereinbefore set forth.

We claim:

1. Coin-actuated mechanism for gas and similar meters adapted for selective actuation by either of two coins, such as a shilling and a penny, embodying a rotary coin holder provided with separate and adjacent coin slots and separate strikers for actuation by the respective coins, said strikers having coin pockets so relatively arranged for coaction with the coins that the striker corresponding to the coin of smaller value is adapted to be independently operated by such coin while the striker for the coin of higher value when actuated thereby causes also the simultaneous actuation of the first striker.

2. Coin-actuated mechanism for gas and similar meters, according to claim 1, wherein the coin holder is arranged within a casing and wherein the pocket for the coin of lower value maintains the coin without displacement from its position in the pocket during rotation of the coin holder, while the pocket for the coin of higher value is open to the adjacent pocket of the coin of lower value so that in the rotation of the coin holder after the insertion of a coin of the higher value the coin is caused to tilt or incline in the pocket by engagement with a portion of the coin holder casing and is thus maintained in a position to be discharged from the coin holder casing after rotation of the coin holder through the same angle as that required to discharge a coin of the lower value.

3. Coin-actuated mechanism for gas and similar meters, according to claim 1, in which the strikers for the coins of different value are disposed in the coin holder in the same plane and are movable transversely to the axis of the coin holder, their form being such that while the one striker may be moved independently of the other, movement of the second striker involves also movement of the first striker.

4. Coin-actuated mechanism for gas and sim-

ilar meters, according to claim 1, wherein the strikers are provided with transversely disposed parts forming the bottom walls of the respective coin pockets, the transverse part of the second striker being disposed above and lying upon the transversely disposed part of the first striker.

5 5. Coin-actuated mechanism for gas and similar meters, according to claim 1, wherein the strikers are provided with transversely disposed parts forming the bottom walls of the respective coin pockets, and in which the transverse part of the first striker is of greater width than the transverse part of the second striker so that the transverse part of the second striker forms a bounding wall of the coin pocket of the first striker.

10 15 6. Coin-actuated mechanism for gas and similar meters, according to claim 1, wherein the strikers are provided with transversely disposed parts forming the bottom walls of the respective coin pockets, and wherein the transverse part of the second striker is provided with a laterally

disposed upstanding portion forming a boundary wall of the coin pocket of the second striker and of such form that the coin contained in the said pocket may incline so that the outer part of its periphery lies within the space forming the coin pocket of the first striker.

10 15 7. Coin-actuated mechanism for gas and similar meters, according to claim 1, wherein the strikers are provided with transversely disposed parts forming the bottom walls of the respective coin pockets, and wherein the transverse part of the second striker is provided with a laterally disposed upstanding portion forming a boundary wall of the coin pocket of the second striker, said upstanding portion being provided with an inclined inner face to support the coin so that the coin contained in the said pocket may incline so that the outer part of its periphery lies within the space forming the coin pocket of the first striker.
